STAND FOR DRESS FORMS AND THE LIKE

Ralph F. Palmer, Montclair, N. J., assignor to The Singer Manufacturing Company, Elizabeth, N. J., a corporation of New Jersey

Application April 23, 1946, Serial No. 664,243

11 Claims. (Cl. 223—120)

1

This invention relates to stands for dress-forms and the like, and more particularly for dress-forms comprising hollow shells conforming to the contours of human models.

The invention has as its primary object to provide an improved stand facilitating the mounting thereupon of hollow dress-forms of various shapes, sizes and proportions, and insuring a firm support for the dress-form mounted upon the stand. More specifically, the invention aims to provide a dress-form stand requiring a minimum of adjustment thereof to adapt the stand for use with hollow dress-forms of different sizes and postures.

Another object of the invention is to provide, in a stand of this nature, simplified and improved means for simultaneously locking, in their adjusted positions, all of the adjustable arms which engage the lower portion of the dress-form and which hold the form against lateral movement.

Another object of the invention is to provide an improved neck-frame for the stand which will accommodate the entire range of neck sizes and which will automatically adapt itself to the particular angle or inclination of the neck portion of each individual dress-form placed thereon.

A further object of the invention is to provide a stand of this nature which is more stable than those heretofore provided; which is neat in appearance and which is of low cost of manufacture.

A still further object is to provide a stand of this nature which is so constructed that it is adapted to be disassembled and packed into relatively small compass for the purpose of transportation and storage.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a side elevation of the improved stand, with a dress-form supported thereby shown in vertical section.

Fig. 2 is an enlarged horizontal sectional view of the stand taken on the line 2—2 of Fig. 1, illustrating in full and dotted lines the adjustment of the arms which engage the lower portion of the dress-form.

2

Fig. 3 is an enlarged vertical section of the mid-portion of the improved stand, showing more particularly the means for clamping the dress-form engaging arms in adjusted positions, the means for effecting vertical adjustment of the standard and the means for locking the upper portion of the standard against rotation relative to the lower portion thereof.

Fig. 4 is a horizontal sectional view taken on the line 4—4 of Fig. 3.

Fig. 5 is an under side view of the hub portion of the standard base illustrating the means for securing the lower portion of the standard and the three legs of the base in said hub portion.

Fig. 6 is a perspective view of one of the clamping elements for the dress-form supporting arms.

Fig. 7 is an enlarged vertical sectional view of the improved neck-frame showing it supported for universal adjustment on the upper end of the standard.

Fig. 8 is a still further enlarged sectional view of the neck-frame taken on the line 8—8 of Fig. 7.

Referring more specifically to the drawings, the invention is disclosed as embodied in a stand comprising a base B, an upright standard S, supported by the base, a dress-form supporting neck-frame N adjustably mounted upon the upper end of the standard and a vertically and horizontally adjustable dress-form skirt-support D secured upon the standard and adapted to engage the inner surface of the skirt portion of a dress-form F to hold the latter against lateral movement.

The base comprises a substantially cylindrical hub member 1, preferably of solid metal and weighing in the neighborhood of six pounds. The hub member is formed with a central bore 2, adapted to receive the lower end of the outer tubular member 3 of the standard S, and three pairs of vertically spaced radial sockets 4 adapted to receive the opposite end portions 5^a of three bent metal legs 5. The member 3 is maintained in the bore 2 by a set screw 6 threaded radially in the hub 1, while the legs 5 are held in the hub 1 by set screws 7 threaded into the lower end of the hub and bearing against the lowermost end portions 5^a of the legs. Due to the weight of the hub 1 and its location at the bottom of the standard and close to the axis thereof, together with the substantial spread of the three legs 5, the entire stand is extremely stable, even when adjusted to its uppermost position.

The standard S is made of two major parts, vis. the tubular member 3 and a rod 8 telescopically mounted therein. At its upper end the rod

8 carries a ball 9 upon which the neck frame N is mounted for universal movement. The neck-frame is of generally truncated conical form and comprises upper, intermediate and lower ring members 10, 11 and 12, respectively, united by wire loops 13 secured to the ring members as by soldering or welding. A socket is provided for the ball 9 by two wire-loops 14 and 15 embracing and secured to the upper ring member 10 and extending substantially centrally thereacross. The lower straight limbs 14^a and 15^a of the loops 14 and 15 are resilient and are so spaced as to permit the ball 9 to be inserted therebetween after which the bars assume the position shown in Figs. 7 and 8. The upper limbs of loops 14 and 15 are bent upwardly as at x to overlie the ball 9. Thus the neck frame is universally mounted on the standard S and may adapt itself to the particular angle or inclination of the neck-portion n of any individual dress-form placed thereon. The neck-frame is of tapered form and is of such length and of such diameters at its opposite ends as to accommodate the entire range of neck sizes.

As above stated the rod 8 is telescopically mounted in the tube 3. The rod 8 and the dress-form carried thereby may be adjusted vertically, at will, and maintained at any desired elevation. This is effected by a clamp device designated generally as C, which, as shown most clearly in Figs. 3 and 4, comprises a sheet metal member c generally C-shaped in vertical section and including lower and upper disk-like portions 16 and 17, respectively, and an intermediate connecting portion 18, substantially U-shaped in cross section. The portions 16 and 17 are provided with flat-sided apertures 16^a, 17^a which, as shown in Figs. 3 and 4, are slidably fitted upon the rod 8 which also is provided with flat sides 8^a. The engagement of the flat sides of the apertures 16^a, 17^a with the flat sides of the rod 8 prevents relative rotation between the rod and the clamp member c.

The disk 16 is formed with a plurality of peripheral notches 16^b adapted to be engaged by the upper end portion 18^a of an L-shaped latch lever 18 fulcrumed on a stud 19 carried by a bracket 20, welded or otherwise secured to the tube 3 adjacent the upper end thereof. A coil spring 21 engaging the bracket and the latch lever 18 normally maintains the lever in engagement with one of the notches 16^b, as shown most clearly in Fig. 3. The latch lever 18 is also formed with a portion 18^b adapted to be grasped between the thumb and finger of a user to swing the latch lever downwardly, in opposition to the spring 21, to release the lever from the disk 16 thereby to permit rotation of the rod 8, and the dress-form carried thereby, relative to the base B and tube 3.

The rod 8 and the dress-form F are normally held against vertical adjustment by a pair of clamping levers 22 apertured at 22^a to receive the rod 8 and having their ends 22^b projecting through and fulcrumed in slots in the portion 18 of the clamp member c. The levers 22 are normally biased away from each other by a coil spring 23 located therebetween and surrounding the rod 8. Thus the walls of the apertures 22^a are normally caused to impinge upon the rod 8 and prevent endwise movement of the rod relative to the clamp member c. By pressing the levers 22 together, in opposition to the spring 23, the levers are caused to free the rod 8 which, together with the dress-form F, may then be adjusted vertically.

As hereinbefore stated, the lower or skirt portion of the dress-form is adapted to be engaged by a device designated generally as D to hold the dress-form in the proper vertical position and prevent lateral movement thereof. This device comprises two pairs of transversely arranged adjustable supports f and s, the former being adapted to engage the inside of the dress-form from front to back and the latter being adapted to engage the inside of the form from side to side. Improved means are provided for adjusting this device vertically on the rod 8 to accommodate dress-forms of different lengths and to clamp the form-engaging arms in their various positions of adjustment. This device includes a sleeve 24 (Fig. 3) slidably mounted on the rod 8 and having its exterior threaded, as at 24^a, to receive a clamp nut 25. The lower end portion of the sleeve is tapered and split, as indicated at 26 to form, in effect, a three-jaw chuck. The lower end of the nut 25 is correspondingly tapered as at 25^a. Thus screwing of the nut upwardly on the sleeve 24 causes the chuck-jaws to be deflected inwardly, thereby causing them to grip the rod 8 and thereby lock the entire device D to the standard.

The dress-form supports f and s are similar in construction and differ only in the length thereof, the side-to-side support s being somewhat longer than the front-to-back support f.

Each of the supports f and s comprises two identical U-shaped members M each having one of its legs in the form of a tube 27 and its other leg as a solid bar 28, the outside diameter of which is slightly less than the inside diameter of the tube. The members M are assembled with the solid leg 28 of one inserted into the tubular leg 27 of the other, thus producing a substantially rectangular frame which is adjustable as to length.

The dress-form supports f and s are secured to the standard S and held in their adjusted position by a clamp device comprising upper and lower stamped sheet metal clamp members 29 and 30 having uppermost pairs of opposed arcuate clamp jaws 29^a and 30^a, respectively, adapted to grip between them the tubular legs 27 of the support s and lowermost pairs of opposed arcuate clamp jaws 29^b and 30^b, respectively, adapted to grip between them the tubular legs 27 of the support f.

As shown most clearly in Figs. 2 and 3 the upper clamp member 29 is riveted or otherwise secured, at t, upon the upper end of the sleeve 24. The lower clamp member 30 is formed with a central aperture 30^c through which the upper end portion of the sleeve 24 extends. The clamp member 30 rests upon the upper end of a clamp nut 31 threaded on sleeve 24, and when that nut is screwed upwardly on the sleeve it forces the clamp member upwardly relative to stationary clamp member 29 thus simultaneously clamping all of the tubular members 27 of skirt-support D. When the nut 31 is loosened the telescoping elements of the skirt-supports may be adjusted endwise, for example, as indicated in dotted lines in Fig. 2, to cause the outer ends of those elements to engage the inner surface of the skirt portion of the dress-form and hold the form against lateral movement. The amount of endwise adjustment provided between the members 27 and 28 of the supports f and s is sufficient to accommodate the entire range of dress-form sizes.

The stand readily may be disassembled, for the purpose of shipping, storing etc., by merely

removing the neck-frame; withdrawing the bars 28 of the members M from the tubes 27 of the complementary members M; withdrawing the rod 8 from the tube 3; and finally loosening the set screws 6 and 7 and removing the tube 3 and legs 5 from the hub 1. When so disassembled the component parts of the stand may be packed in a relatively small space.

From the foregoing it will be perceived that this invention has provided an improved stand for dress-forms and the like, which is simple in construction; efficient in operation; easy of adjustment; which will accommodate the entire range of dress-form sizes; and which may be manufactured and sold at a relatively low price.

Having thus set forth the nature of the invention, what I claim herein is:

1. In a stand for dress-forms and the like, having a base, a standard, and means on the standard for supporting a dress-form; means engaging the lower portion of the dress-form for preventing lateral movement thereof relative to the standard comprising a plurality of lengthwise adjustable arms carried by said standard and a single clamp means for simultaneously securing all of said arms in their adjusted positions.

2. In a stand for dress-forms and the like, having a base, a standard, and means on the standard for supporting a hollow dress-form; means carried by the standard and engaging the inner face of the lower portion of the dress-form to hold the dress-form against lateral movement relative to the standard comprising a plurality of pairs of transversely arranged and lengthwise adjustable arms, a pair of clamp elements engaging all of said arms, and a single screw device acting on one of said clamp elements to cause said clamp elements simultaneously to grip all of said arms to hold them in their adjusted positions.

3. In a stand for dress-forms having a standard and means on the standard for supporting a dress-form; a base for supporting said standard and comprising a relatively heavy, vertically disposed and substantially cylindrical hub member formed with an axial socket adapted to receive the lower end of the standard and a plurality of pairs of upper and lower radially and horizontally disposed sockets equally spaced about said hub member, a plurality of bent metal leg members each having horizontally arranged and parallel opposite end portions fitted into a pair of said sockets and floor-engaging foot portions intermediate said end portions, and set screws threaded into said hub member and bearing on said standard and said leg members for holding said standard and leg members in said sockets.

4. In a stand for dress-forms having a base, a vertical standard supported by said base, and means at the upper end of said standard for engaging and supporting a hollow dress-form; dress-form steadyng means carried by the standard and engaging the inner surface of the lower portion of said dress-form comprising a pair of complementary U-shaped members each having legs of unequal diameters, the larger leg of each member being tubular and the smaller leg being telescoped into the larger leg of the complementary member; and means carried by the standard for securing said members in their adjusted positions.

5. In a stand for dress-forms having a base, a vertical standard supported by said base, and means at the upper end of the standard for sup-

porting a hollow dress-form; dress-form holding means carried by the standard and engaging the inner surface of the dress-form for holding the dress-form against lateral movement relative to the standard comprising a sleeve mounted on said standard, a first clamp plate fixedly secured to said sleeve and provided with a pair of stationary clamp-jaws, a second clamp-plate slidably mounted on said sleeve and having clamp-jaws complementary to the first named jaws, a pair of U-shaped dress-form-engaging members, having a telescopic connection with each other, located between said stationary and movable clamp-jaws, and means for effecting relative movement between said clamp plates to cause said clamp-jaws to grip said members.

6. In a stand for dress-forms, a dress-form holding means as set forth in claim 5 in which the sleeve which carries the clamp-plates is exteriorly threaded and has one end-portion split to form chuck-jaws, and in which a nut threaded on said sleeve compreses said chuck-jaws to cause them to grip the standard to hold the dress-form-engaging members at various elevations on said standard.

7. In a stand for dress-forms, a dress-form holding means as set forth in claim 5 in which the clamp plates, carried by the sleeve mounted on the standard, are provided with two sets of complementary clamp jaws arranged at different elevations; in which two pairs of telescopically mounted dress-form-engaging members are fitted into said clamp-jaws perpendicular to each other; and in which a single means causes said clamp-jaws to grip all of said members simultaneously.

8. In a stand for dress-forms, a dress-form holding means as set forth in claim 5 in which the means for causing relative movement between the clamp plates, to cause them to grip the dress-form-engaging members, comprises a nut threaded on the outside of said sleeve and engaging the movable clamp plate; and in which a second nut threaded on said sleeve has a tapered bore which engages the sleeve to constrict the sleeve and cause it to bind upon the standard.

9. In a stand for dress-forms, a dress-form holding means as set forth in claim 5 in which the standard is formed of a tubular member secured in the base and a rod telescopically mounted in the tubular member; and in which the sleeve which carries the dress-form holding means is slidably mounted upon and adapted to be secured to said rod.

10. A stand for dress-forms and the like comprising a base; a vertically disposed standard rising from said base; and a rigid neck-frame of truncated conical form supported for universal movement on the upper end of said standard and adapted to fit into the neck portion of a dress-form, the smaller end of said neck-frame being only slightly less in diameter than the smallest neck portion of any dress-form to be placed thereon, and the length and the greater diameter of said neck-frame being substantially twice the smaller diameter thereof, whereby the neck-frame is proportioned to accommodate the entire range of neck sizes of dress-forms adapted to be placed thereon.

11. A stand for dress-forms and the like comprising a base; a vertically disposed standard rising from said base; a substantially spherical

ball secured upon the upper end of said standard; a wire neck-frame of truncated conical form having upper and lower end rings and intermediate wires connected to said end rings; and a pair of spaced apart wire loops extending across the upper end of said neck-frame and secured thereto, the upper portions of said loops overlying and resting upon said ball to support said neck-frame thereof and the lower portions of said loops resiliently engaging said ball below the center thereof.
